MODULAR INSTRUMENT PANEL FOR A BOAT OR THE LIKE

Richard J. McFadyen, Upper Montclair, N.J., assignor, by
mesne assignments, to Aqua Meter Instrument Corpora-
tion, Roseland, N.J., a corporation of New Jersey

Filed Sept. 27, 1961, Ser. No. 66,884

Term of patent 14 years

(Cl. D52—6)

FIG. 1

FIG. 2

FIG. 3

FIG. 4

FIG. 5

FIG. 1 is a front elevational view of a modular instrument panel for a boat or the like showing my new design;

FIG. 2 is a top plan view thereof;

;

FIG. 3 is a bottom plan view thereof;

;

FIG. 4 is a view taken from the left side of FIG. 2;

;

and

FIGURE 5 is a fragmentary vertical cross-sectional view taken through the center of the circular portion thereof taken along lines 5—5 of FIGURE 1.

The side not shown is substantially like the side shown.

I claim:

The ornamental design for a modular instrument panel for a boat or the like, as shown and described.
